UNITED STATES PATENT OFFICE.

SAMUEL RANDELL, OF FINCHLEY, LONDON, ENGLAND.

COIN-DELIVERY MACHINE.

No. 914,510.

Specification of Letters Patent.

Patented March 9, 1909.

Application filed July 6, 1908. Serial No. 442,214.

To all whom it may concern:

Be it known that I, SAMUEL RANDELL, a subject of the King of England, residing at Finchley, London, in England, have invented certain new and useful Improvements in Coin-Delivery Machines, of which the following is a specification.

This invention relates to machines for the delivery of coin for use for example in giving definite amounts of change or paying out various sums for wages or the like and has for its object to simplify the construction of such machines and render the machine less liable to get out of order.

According to this invention the machine comprises a series of keys a series of bell crank levers each operated by the depression of a key, a series of selective strips one or more of which is positioned by the movement of a bell crank lever on the depression of a key the positioning of the selective strips causing one or more of a series of pins to be moved along a rock shaft. These pins are so mounted on the rock shaft that while they can be moved along it they must rotate with it rotation being imparted to the rock shaft on the depression of each key. A series of ejector rods are so disposed that they can each be engaged and operated by one of the pins on the rock shaft when this pin has been moved along the rock shaft by the positioning of the selective strips. The end of each ejector rod can enter into one of a series of coin troughs and eject one or more coins therefrom the coins conveniently falling thence into a chute or suitable receptacle. There is preferably combined with each ejector rod a device whereby the end of the rod is caused to drop after a coin has been ejected so that the end of the rod is relieved from the weight of the pile of coins during its return movement this return movement being effected either positively by the operation of the rock shaft or by spring action.

The coin troughs are conveniently all so mounted that they can remove together from the machine thus enabling the contents to be easily transferred either from one machine to another or to a safe this arrangement also facilitating refilling the coin troughs.

The machine can be used with any known system of coinage but in the accompanying drawings is illustrated and described as being constructed for use with the English coinage. The adaptation of the machine for use with coinage on the decimal or other

system is clearly easily effected by rearrangement of the parts, the general operation of the mechanism remaining the same in each case.

Figures 1 and 1^a represent a front elevational view of a change giving machine constructed in accordance with this invention, part of the main casing being removed. Figs. 2 and 2^a represent a plan view of the same. Figs. 3 and 3^a are front elevational views of the machine with that portion of the inner casing carrying the coin chutes removed. Fig. 4 is a sectional end elevation on the line 4—4 of Fig. 2^a. Fig. 5 is a perspective view of a detail on an enlarged scale. Fig. 6 is a perspective view of a device for giving a drop motion to the ends of the ejector rods. Figs. 7 and 7^a represent a sectional plan view on the line 7—7 of Fig. 4. Fig. 8 is a view on an enlarged scale of the operative connection between the key rods bell crank levers selective bars and rocking bar. Fig. 9 is an end view of the same detail of the mechanism. Fig. 10 is a side elevation of one of the bell crank levers. Fig. 11 is a front view of the same. Fig. 12 is a plan of the same. Figs. 13, 14 and 15 are similar views of another type of bell crank lever. Fig. 16 is a detail on an enlarged scale of the pinion co-operating with the rocking bar quadrant. Figs. 17, 17^a and 17^b represent perspective views of the several selective strips. Fig. 18 is a perspective view of the mechanism for returning the selective strips after operation of the keys. Fig. 19 is a perspective view of a modification of the device for giving a drop motion to the ends of the ejector rods. Fig. 20 is a similar view showing the parts of this mechanism in the position assumed by them after ejection has taken place.

Like letters indicate like parts throughout the drawings.

The apparatus described hereunder is closed in by a casing which prevents unauthorized access being had to the contents of the coin troughs and excludes dust but in the present description and illustrations this casing is omitted for the sake of clearness. This casing may obviously vary in its construction and arrangement according to requirements. The machine has a main frame comprising end plates A connected by a longitudinal member A' which carries the selective strips and by a second longitudinal member A² which is of channel section and,

carries the key actuated levers. There is further a front plate B the ends of which are rigidly secured to the end plates A. This front plate B is curved and carries the 6 coin troughs B' each of which is partially inclosed so as to retain the coins in position and allow them to be fed by gravity to the points whence they are ejected. The upper end B² of each coin trough is open to allow 10 of the ready insertion of coins. The lowermost coin in each trough rests on a plate or annular flange B³ above which is an opening B⁴ of such dimensions that the coin can be ejected therethrough whence it falls into 15 a hopper C being delivered through an opening C' into the hand or any receptacle which may be placed thereunder. At the back of each coin trough opposite the point where the lowermost coin will lie is an opening B⁵ 20 in which lies the end D' of an ejector rod D. Each of these rods is free to be moved longitudinally passing through a carrying plate A³ which runs between the end plates A. The rear end of each ejector rod D is 25 curved round as at D² to form a slot D³ which is transverse to the path of motion of the ejector rod.

Above the hooked rear ends of the ejector rods is disposed a bar E which rocks in 30 bearings E' formed in the end plates A. On this bar E are mounted a series of collars E² each carrying a pin E³ the end of which can engage the slot D³ in the rear end of a corresponding ejector rod D. The bar E 35 is of square or similar cross section or provided with a feather so that the collars E² with their pins E³ must partake of the rotary motion imparted to the bar E in the manner hereafter described, the collars E² 40 however being a sufficiently loose fit on the bar E to allow of these collars being moved longitudinally along the bar E. By this longitudinal movement the pins E³ are caused to engage with the slots D³ of the 45 ejector bars or kept clear of these slots and it will be seen therefore that since on the depression of each key rocking motion is imparted to the bar E in the manner to be hereinafter more particularly detailed the pins 50 E³ by their oscillatory motion will tend to impart longitudinal movement to the ejector rods D. Such movement will not however actually be imparted to the rod D unless the collar E² of the pins E³ corresponding to this 55 ejector rod has been moved along the bar E so as to bring the pin E³ into engagement with the slot D³. The rod thus engaged will therefore move forward and return with the rocking motion of the bar E. It is to be 60 noted that the extremity of the hooked portion D² of each rod D lies at the back of its corresponding pin E³ when the latter and its collar E² is in a position such that the pin E³ is inoperative to move the rod D in 65 the forward direction. The pin E³ is how-

ever able to operate on the end D² of the rod D to move the latter inward and to return it to its normal position of rest should this rod D have received accidentally or otherwise an outward movement. Thus the mechanism automatically insures the retention of the ejector rods in their positions of rest without the aid of springs or weights for each individual ejector rod. The disposition 70 of the hooked end D² also makes certain that each ejector rod is returned to its normal position even if the collar E² and pin E³ should be in process of returning to their normal inoperative positions wherein the pin E³ is out of engagement with the slot 75 D³. This allows of rapid operation of the machine. Above the rocking bar E lie the selective strips F in number corresponding to the number of collars and pins on the 80 rocking bar E this number of course coinciding with the number of ejector rods and coin troughs. 85

Each selective strip is conveniently formed of a flat piece of metal so that all the strips will lie side by side in the manner clearly 90 illustrated in Figs. 4 and 5 and thus occupy a very small space laterally. Certain of these strips are shorter than others. The ends of the longer strips project through openings in each end plate A of the machine 95 being carried at an intermediate point by a bracket A⁴ on the longitudinal member A'. The shorter selective strips have one end projecting through the left hand end plate A and are supported by that plate and the 100 bracket A⁴. Projecting laterally from the under edge of each strip F are two arms F' which lie on either side of one of the collars E². On the upper edge of each strip F one or more projections F² are formed. The 105 number and disposition of these projections is such as to insure the selection of the necessary strip or combination of strips required to effect the delivery of the coins necessary to make up the total sum which is to 110 be delivered at each manipulation of the machine.

Over the selective strips are carried in the channel frame A² previously referred to a series of bell crank levers which communicate the motion of the keys to the selective strips and effect the selection of the necessary combinations of the latter. Each of these bell crank levers comprises an arm G having a rounded nose G' and adjacent 115 thereto a flat G². The second arm G³ is of shape and width corresponding to the number of selective strips F whose projections F² this arm G³ is to engage. The arms G and G³ are formed on a body portion G⁴ 120 which is mounted on a spindle G⁵ whose ends lie in bearings formed in the channel member A². 125

Each key H is disposed on the upper end of a key rod H' whose lower end is cut into 130

a nose H^2 adapted to bear upon the flat G^2 of the arm G of a bell crank lever. The lower end of each key rod H' passes through a corresponding opening in the channel 5 member A^2 which thus forms a guide for the key rod the upper portion of the key rod being guided in a plate A^3 which closes in the top of the apparatus around and below the keys. A coiled spring H^3 is 10 posed around each key rod H' the lower end of this spring bearing on the member A^2 while the upper end is either attached to the rod H' or bears against a collar formed thereon. These springs H^3 serve to return 15 the keys to their normal position after they have been depressed.

Each key rod is provided with a lateral projection H^4 which lies over a rod J which runs throughout the length of the machine 20 between the two rows of key rods. The ends of the rod J are carried on a quadrant K pivoted at K' on the frame plates A . The periphery of this quadrant is toothed and engages with a pinion L mounted on a stud 25 L' on the side plate A . A lever arm L^2 is carried by this pinion and rotates therewith having pivoted to its end at L^3 a link M whose other end is pivotally connected to the end of a lever arm E^4 mounted on the 30 rocking bar E . A second lever arm E^5 is also mounted on the rocking bar and has connected to its end a coiled spring N whose other end is secured at N' to the frame plate A . There is a quadrant K pinion L 35 with links M and lever arms E^4 E^5 with spring N at each end of the apparatus.

The operation of the mechanism above described is as follows:—When a key H is depressed during the initial downward movement of the key rod H' the end H^2 of this key rod bears against the flat G^2 of the arm G of its bell crank lever and moves this lever about its spindle G^3 . This movement causes longitudinal movement of the selective strip 40 or strips F with whose projection or projections F^2 the arm G^3 of the bell crank lever engages. This results in the lateral movement of one or more of the collars E^2 with their pins E^3 on the rocking bar E thus 45 moving a pin E^3 into engagement with the slot D^3 of an ejector D . At the moment when the bell crank lever G G^3 has moved to an extent sufficient to insure the required positioning of the selected collar or collars 50 E^2 and pin or pins E^3 the bell crank lever G G^3 is in the position shown in dotted lines in Fig. 8. It will then be seen that the continued downward movement of the key rod causes the end H^2 of this rod to slide off the 55 flat G^2 and over the rounded nose G' of the lever arm G so that further downward movement of the key rod is possible though further movement of the bell crank lever cannot and does not take place, this lever being also locked against return movement by

the nose of this lever bearing against the side of the key rod H' as shown in dotted lines in Fig. 8. At the stage in its downward movement when the key rod ceases to operate on the bell crank lever the lateral projection H^4 70 on the key rod bears upon the rod J and the continued downward movement of the key rod causes the rod J to be depressed and consequently the quadrant K to be moved about its pivot K' . This results in rotation of the 75 pinion L whereby through the link M and lever arm E^4 rocking motion is imparted to the bar E together with the pins E^3 carried thereon. As a result of this each pin E^3 which may have been positioned to engage 80 with a slot D^3 of an ejector rod D imparts longitudinal movement to that ejector rod with the result that a coin in the trough controlled by this ejector rod is thrown out into the hopper C . On releasing the key which 85 has been depressed the parts are returned to their normal positions the rocking bar E being returned by the spring N the pins E^3 simultaneously drawing back the ejector rod or rods D which have been operated. The 90 quadrant simultaneously is thrown back into its position of rest the key rising under the influence of the spring H^3 . The selective strip or strips F which have been moved also return to their initial positions carrying with them the bell crank lever G G^3 95 which was operated by the depression of the key. The return of these selective strips F is automatically effected by the mechanism shown more particularly in Fig. 18. 100

In each selective strip there is formed a notch F^3 all the notches F^3 being so positioned that when in line all the selective strips are in their normal positions ready for setting. Engaging with the notches F^3 105 is a broadened end O' of one arm O of a bell crank lever pivoted on a bracket mounted on the plate A^2 . The lever arm O passes through a slot A^5 in this plate. Two bars Q lie along outside the key rods H' so that they are positioned beneath lugs H^5 formed in the key rods so that on the depression of a key the lug H^5 will bear 110 on one or other of the rods Q . These rods are carried at their ends in frames Q' provided with projecting arms Q^2 which pivot on a stay rod R . To a lever arm Q^3 connected to the radius arm Q^2 of the frame Q' is a spring Q^4 . The rods Q are thus 115 mounted so that they can swing about the stay rod R when a key is depressed the spring Q^4 lifting the rods Q back to their normal raised positions after a key has been depressed. One of the frames Q' is connected with the second arm O^2 of the bell 120 crank lever which returns the selective strips the connection between the lever arm O^2 and the frame Q' being such as to allow the necessary relative movement but insure the depression of the frame Q' imparting 125 130

motion to the bell crank lever $O O^2$. This mechanism operates as follows:—When a key is operated its initial downward movement causes depression of the frame O' owing to the lug H^2 of the key rod bearing on one or other of the rods Q . This arm of the frame Q' causes the lever arm $O O'$ to swing backward out of the notches F^2 in the selective strips F which are then free to be positioned in the manner already described. On releasing a key the rods Q and bell crank lever $O O'$ return to their normal positions under the influence of the springs Q^4 and the selective strips are shifted back into their positions of rest by the end O' of the lever arm O .

As has been mentioned previously the ejector rods D may conveniently have a movement imparted to their ends which push the coins from the troughs so that after ejection of a coin the end of each rod will drop so as to be relieved of the weight of the coins remaining in the trough. A device for effecting this movement is illustrated in Figs. 4 and 6 the latter being a perspective view of the mechanism by itself. The forward ends D' of the ejector rods D are passed through openings in a rocking plate A^6 which is pivoted at A^7 on the side plates A of the machine. A stop A^8 limits the movement of the rocking plate A^6 in one direction while a pin A^9 limits the movement of this plate in the other direction. The plate A^6 as seen is bent to rather more than a right angle. At one end of the plate A^6 and on its upper edge is formed a lug A^{10} having a hole in it through which passes the end of a rod E^6 pivotally connected to the lever arm E^3 mounted on the rocking bar E . A pin E^7 projects from the extreme end of the rod E^6 which lies beyond the hole in the lug A^{10} a second pin E^8 being positioned on the rod E^6 at the inner side of the lug A^{10} . A spring A^{12} bears on the rocking plate A^6 in such a manner as to hold it either against the stop A^9 or against the stop A^8 according to the position into which the plate A^6 has been moved.

50 The operation of the device is as follows:—After positioning a pin E^8 so as to engage one of the ejector rods D the bar E rocks in the manner described and the rod D is moved longitudinally through the plates A^8 and A^6 so that a coin is pushed out into the hopper C . The rod E^6 of course partakes in the forward movement which is imparted to the ejector rod D and just as the latter is completing the ejection of a coin the stop E^8 comes in contact with the lug A^{10} and the plate A^6 is rocked with the result that a slight downward movement is given to the end D' of the ejection rod D . The parts have now assumed the positions shown in dotted lines in Fig. 4. The plate A^6 re-

mains in this position being acted on by the spring A^{11} so that the rod D as it is withdrawn owing to the return rock of the bar E will lie in a position such that its end D' is below and clear of the weight of the pile 70 of coins in the trough. The return of the ejector rods is thus considerably facilitated and the power necessary to effect this return reduced. Just as the rocking shaft E with the parts controlled by it is reaching 75 its normal position the pin E^7 carried by the rod E^6 comes in contact with the lug A^{10} with the result that the plate A^6 is drawn back against the plate A^9 into its initial position. The end D' of the ejector rod D is 80 thus lifted into position ready to operate on the next lowermost coin in the pile held in the trough. Figs. 10 to 15 illustrate different constructions of key actuated bell crank levers for effecting the selection of the required strip or combination of strips F . 85 Figs. 10, 11 and 12 illustrate a bell crank lever having the arm G on the opposite side to that shown in the construction of levers illustrated in Figs. 8 and 9. It will be understood that the bell crank levers are arranged in rows corresponding to the two rows of keys. In some cases in order to effect the necessary combination of strips 90 corresponding to a money value as indicated 95 on a key it is necessary to actuate more than one bell crank lever on the depression of a single key and this is effected by providing the lever arm G^3 with a lateral lug or projection G^6 as shown in Figs. 13, 14 and 15. 100 This lug G^6 lies opposite to the lever arm G^3 of an adjacent bell crank lever but in another row and it will be seen that when a bell crank lever provided with a lug G^6 is depressed this lug by operating on the lever 105 arm G^3 of the companion lever will cause this latter lever also to be moved and consequently the strip or strips controlled by this lever to be positioned, as well as that strip or strips which are controlled by the 110 lever arm which carries the lug. By reason of the lug G^6 lying over the face of the arm of the second bell crank lever this lever is free to be moved independently when the key controlling it is operated.

In Fig. 17, are shown the several selective strips with the values of the coins controlled by each strip indicated against them. It will be seen that these money values are such that the necessary combination can be 115 made with them to deliver any desired sum up to the limit of the machine. The coins are conveniently arranged in the troughs B' B^2 in the following order taking the troughs from left to right as they are indicated in 120 Fig. 1. Sovereigns are placed in the first three troughs but coins are ejected from the first two troughs when combinations involving two pounds are required. In the fourth trough are placed half sovereigns. The 125 130

next two troughs each contain half crowns and the next two following each contain two shilling pieces. The shillings are deposited in the next trough followed by six-pences, threepenny pieces and two troughs containing pennies and one containing half-pennies. The arrangement is such that if it is desired for example to deliver two pounds a sovereign is ejected from each of the first two troughs. If three pounds are to be given by the machine a sovereign is delivered from each of the first three troughs. It will be seen that in the same way by combining the above mentioned values of coins in different ways any desired sum to the limit of the machine can be delivered.

In the modification of the device for giving drop motion to the ends of the ejector rods as shown in Figs. 19 and 20 the drop plate A⁶ which lies beneath the ejector rods D toward their outer ends is mounted on a pivot rod A⁷ so that it can freely rock when a lever arm A¹² projecting from the end of the pivot A⁷ is released. The plate A⁶ may of course be dropped by spring action but in practice it is found to be sufficient to allow the weight of the plate A⁶ to bring about the drop motion. The lever A¹² in the position of rest is held as shown in Fig. 19 by a spring catch S mounted on the side plate A of the machine. This spring catch is adapted to be moved so as to release the arm A¹² when an ejector rod D has just completed its ejection motion when the plate A⁶ is at once free to drop together with the end of the ejector rod. The releasing of the arm A¹² is conveniently brought about in the following way. A two armed rocking lever is mounted on the side plate A of the machine one arm S' of this lever bearing against the spring catch S while the other arm S² engages with a slot E⁹ formed in the rod E⁶ which as in the previously described construction is pivotally connected at one end to the arm E⁵ carried by the rock shaft E. The rod E⁶ is guided in a slotted plate S³ mounted on the side plate of the machine. In operation it will be seen that as the rock shaft E is operated and an ejector rod D moved so as to effect the ejection of a coin so will the rod E⁶ move and rotate the two armed rocking lever S' S² until the arm S' of this lever presses the catch S back sufficiently to release the arm A¹² when the plate A⁶ together with the ends of the ejector rods supported by it will drop. The rod E⁶ returns to its initial position with the motion of the rock shaft E and a pin E¹⁰ carried preferably in an adjustable manner toward the end of the rod E⁶ lifts the drop plate A⁶ by engaging with the arm A¹² the latter being thereby brought back to its initial position when it snaps over the catch

S and is held until the next ejection takes place.

In the construction shown in Figs. 19 and 20 the operation of the ejector rod D by the pin E³ is modified from that shown in the previously described figures. In this case in place of there being a positive engagement between the pin E³ and the hook D³ in the end of the rod D the rear end of the ejector rod D is formed square and the pin E³ when shifted along the rock shaft E merely strikes the end of the ejector rod D giving it the necessary longitudinal movement. The return motion of the ejector rod is in this case effected by a spring D⁴ one end of which is secured in the rear end of the ejector rod while the other end is attached to the plate or guide bar A³.

The details of construction of the machine as a whole may be varied in many ways to suit different requirements. It is convenient to provide some means for carrying down those coins which are situated in the uppermost part of the troughs so as to insure their descent to the ejector. To this end springs may be employed in some well-known manner.

The return motion of the selective strips may be modified from that illustrated in Fig. 18 by connecting the lever O O' O² directly to the quadrant operating rod J.

As already mentioned the coin troughs are mounted on a common plate and can be removed as a whole from the machine the coin trough carrying plate merely dropping into place and being retained there by its weight.

What I claim as my invention and desire to secure by Letters Patent is:—

1. In a coin delivery machine the combination of a plurality of keys, a plurality of longitudinally movable selective strips, an operative connection between each key and the selective strips, a rock shaft, a plurality of pins so mounted on the rock shaft as to be rotatable therewith but longitudinally movable thereon, an operative connection between the selective strips and the pins on the rock shaft, operative connections between the strip-moving keys and the rock shaft whereby the shaft is rocked when a key is depressed, a plurality of ejector rods each adapted to be engaged and operated by one of the pins on the rock shaft and a plurality of coin troughs into which the ends of the ejector rods can enter as set forth.

2. In a coin delivery machine the combination of a plurality of keys, a plurality of bell crank levers operated by the depression of the keys, a plurality of longitudinally movable selective strips controlled by the bell crank levers, a rock shaft, a plurality of pins so mounted on the rock shaft as to be rotatable therewith but longitudinally mov-

- able thereon, an operative connection between the selective strips and the pins on the rock shaft, operative connections between the strip-moving keys and the rock shaft 5 whereby the shaft is rocked when a key is depressed, a plurality of ejector rods each adapted to be engaged and operated by one of the pins on the rock shaft and a plurality of coin troughs into which the ends of the 10 ejector rods can enter as set forth.
3. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a 15 rock shaft, a plurality of pins so mounted on the rock shaft as to be rotatable therewith but longitudinally movable thereon, an operative connection between the selective strips and the pins on the rock shaft, operative 20 connections between the strip-moving keys and the rock shaft whereby the shaft is rocked when a key is depressed, means for returning the rock shaft to its initial position, a plurality of ejector rods each adapted to be engaged and operated by one of the pins on the rock shaft and a 25 detachable plate carrying a plurality of coin troughs into which the ends of the ejector rods can enter as set forth.
4. In a coin delivery machine the combination of a plurality of keys, a plurality of longitudinally movable selective strips, an operative connection between each key and the selective strips, a rock shaft, a plurality of pins so mounted on the rock shaft as to be rotatable therewith but longitudinally 30 movable thereon, an operative connection between the selective strips and the pins on the rock shaft and a plurality of coin troughs into which the ends of the 35 ejector rods can enter as set forth.
5. In a coin delivery machine the combination of a plurality of keys, a plurality of longitudinally movable selective strips, an operative connection between each key and the selective strips, a rock shaft, a plurality of pins so mounted on the rock shaft as to be rotatable therewith but longitudinally 40 movable thereon, an operative connection between the selective strips and the pins on the rock shaft, operative connections between the strip-moving keys and the rock shaft whereby the shaft is rocked when a key is depressed, a plurality of ejector rods each adapted to be engaged and operated by one of the pins on the rock shaft, means for imparting a drop motion to the outer end of each ejector rod after a coin has been ejected and a plurality of coin troughs into which the ends of the 45 ejector rods can enter as set forth.
6. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a rock 50 shaft, a plurality of pins so mounted on the rock shaft as to be rotatable therewith but longitudinally movable thereon, an operative connection between the selective strips and the pins on the rock shaft, means whereby the shaft is rocked when a key is depressed, a plurality of ejector rods each adapted to be engaged and operated by one of the pins on the rock shaft, means for imparting a drop motion to the outer end of each ejector rod after a coin has been ejected and a plurality of coin troughs into which the ends of the 55 ejector rods can enter as set forth.
7. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a rock 60 shaft, a plurality of pins so mounted on the rock shaft as to be rotatable therewith but longitudinally movable thereon, an operative connection between the selective strips and the pins on the rock shaft, means whereby the shaft is rocked when a key is depressed, a plurality of ejector rods each adapted to be engaged and operated by one of the pins on the rock shaft, means for imparting a drop motion to the outer end of each ejector rod after a coin has been ejected and a plurality of coin troughs into which the ends of the 65 ejector rods can enter as set forth.

rock shaft, a plurality of ejector rods each adapted to be engaged and operated by one of the pins on the rock shaft and a plurality of coin troughs into which the ends of the ejector rods can enter as set forth. 70

6. In a coin delivery machine the combination of a plurality of keys, a plurality of longitudinally movable selective strips, an operative connection between each key and the selective strips, a rock shaft, a plurality of pins so mounted on the rock shaft as to be rotatable therewith but longitudinally movable thereon, an operative connection between each selective strip and a pin on the rock shaft, operative connections between the strip-moving keys and the rock shaft whereby the shaft is rocked when a key is depressed, means for returning the rock shaft to its initial position, a plurality of ejector rods each adapted to be engaged and operated by one of the pins on the rock shaft and a 75 detachable plate carrying a plurality of coin troughs into which the ends of the ejector rods can enter as set forth.

7. In a coin delivery machine the combination of a plurality of keys, a plurality of key rods each movable longitudinally by the depression of a key, a plurality of longitudinally 80 movable selective strips, a plurality of bell crank levers one arm of each of which is engaged by a key rod when a key is depressed,

pressed the other arm of each lever operating to shift one or more selective strips, a rock shaft, a plurality of pins so mounted on the rock shaft as to be rotatable therewith but longitudinally movable thereon, an operative connection between the selective strips and the pins on the rock shaft, means whereby the shaft is rocked when a key is depressed, a plurality of ejector rods each adapted to be engaged and operated by one of the pins on the rock shaft, means for imparting a drop motion to the outer end of each ejector rod after a coin has been ejected and a plurality of coin troughs into which the ends of the 85 ejector rods can enter as set forth.

8. In a coin delivery machine the combination of a plurality of keys, a plurality of key rods each movable longitudinally by the depression of a key, a plurality of longitudinally 90 movable selective strips, a plurality of bell crank levers one arm of each of which is engaged by a key rod when a key is depressed,

pressed the other arm of each lever operating to shift one or more selective strips, a rock 95 shaft, a plurality of pins so mounted on the rock shaft as to be rotatable therewith but longitudinally movable thereon, an operative connection between the selective strips and the pins on the rock shaft, a universal bar disposed in a position to be engaged by the key mechanism when a key is depressed, an operative connection between the universal bar and the rock shaft, a plurality of ejector rods each adapted to be engaged and oper-

ated by one of the pins on the rock shaft and a plurality of coin troughs into which the ends of the ejector rods can enter as set forth.

9. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a rock shaft, a plurality of pins so mounted on the rock shaft as to be rotatable therewith but longitudinally movable thereon, an operative connection between each selective strip and a pin on the rock shaft, means whereby the shaft is rocked when a key is depressed, means for returning the rock shaft to its initial position, a plurality of ejector rods each adapted to be engaged and operated by one of the pins on the rock shaft and a detachable plate carrying a plurality of coin troughs into which the ends of the ejector rods can enter as set forth.

10. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a rock shaft, a plurality of pins so mounted on the rock shaft as to be rotatable therewith but longitudinally movable thereon, an operative connection between each selective strip and a pin on the rock shaft, a universal bar disposed in a position to be engaged by the key mechanism when a key is depressed, an operative connection between the universal bar and the rock shaft, means for returning the rock shaft to its initial position, a plurality of ejector rods each adapted to be engaged and operated by one of the pins on the rock shaft, means for imparting a drop motion to the outer end of each ejector rod after a coin has been ejected and a detachable plate carrying a plurality of coin troughs into which the ends of the ejector rods can enter as set forth.

11. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm but the latter be locked by the key rod until

the rod returns to its position of rest the other arm of each lever operating to shift one or more selective strips, a rock shaft, a plurality of pins so mounted on the rock shaft as to be rotatable therewith but longitudinally movable thereon, an operative connection between the selective strips and the pins on the rock shaft, means whereby the shaft is rocked when a key is depressed, a plurality of ejector rods each adapted to be engaged and operated by one of the pins on the rock shaft and a plurality of coin troughs into which the ends of the ejector rods can enter as set forth.

12. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, a rock shaft, a plurality of pins so mounted on the rock shaft as to be rotatable therewith but longitudinally movable thereon, an operative connection between the selective strips and the pins on the rock shaft, a universal bar disposed in a position to be engaged by the key mechanism when a key has been depressed and a key rod moved to the extent necessary to complete the movement of the bell crank lever operated thereby and position the selective strip or strips controlled by the bell crank lever, an operative connection between the universal bar and the rock shaft, a plurality of ejector rods each adapted to be engaged and operated by one of the pins on the rock shaft, and a plurality of coin troughs into which the ends of the ejector rods can enter as set forth.

13. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, means for returning to their initial positions those selective strips which have been shifted, a rock shaft, a plurality of pins so mounted on the rock shaft as to be rotatable therewith but longitudinally movable thereon, an operative connection between the selective strips and the pins on

- the rock shaft, means whereby the shaft is rocked when a key is depressed, a plurality of ejector rods each adapted to be engaged and operated by one of the pins on the rock shaft, means for returning to their initial positions those ejector rods which have been operated and a plurality of coin troughs into which the ends of the ejector rods can enter as set forth.
14. In a coin delivery machine the combination of a plurality of keys, a plurality of key rods, each movable longitudinally by the depression of a key, a plurality of longitudinally movable selective strips, a plurality of bell crank levers one arm of each of which is engaged by a key rod when a key is depressed the other arm of each lever operating to shift one or more selective strips, means for returning to their initial positions those selective strips which have been shifted, a rock shaft, a plurality of pins so mounted on the rock shaft as to be rotatable therewith but longitudinally movable thereon an operative connection between each selective strip and a pin on the rock shaft, a universal bar disposed in a position to be engaged by the key mechanism when a key is depressed, an operative connection between the universal bar and the rock shaft, means for returning the rock shaft to its initial position, a plurality of ejector rods each adapted to be engaged and operated by one of the pins on the rock shaft, means for imparting a drop motion to the outer end of each ejector rod after a coin has been ejected, means for returning to their initial positions those ejector rods which have been operated and a detachable plate carrying a plurality of coin troughs into which the ends of the ejector rods can enter as set forth.
15. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, means for returning to their initial positions those selective strips which have been shifted, a rock shaft, a plurality of pins so mounted on the rock shaft as to be rotatable therewith but longitudinally movable thereon, an operative connection between the selective strips and the pins on the rock shaft, universal bar disposed in a position to be engaged by the key mechanism when a key is depressed and a key rod moved to the extent necessary to complete the movement of the bell crank lever operated thereby and position the selective strip or strips controlled by the bell crank lever, an operative connection between the universal bar and the rock shaft, means for returning the rock shaft to its initial position, a plurality of ejector rods each adapted to be engaged and operated by one of the pins on the rock shaft, means for imparting a drop motion to the outer end of each ejector rod after a coin has been ejected and a detachable plate carrying a plurality of coin troughs into which the ends of the ejector rods can enter as set forth.
16. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, a rock shaft, a plurality of pins so mounted on the rock shaft as to be rotatable therewith but longitudinally movable thereon, an operative connection between each selective strip and a pin on the rock shaft, a universal bar disposed in a position to be engaged by the key mechanism when a key has been depressed and a key rod moved to the extent necessary to complete the movement of the bell crank lever operated thereby and to position the selective strip or strips controlled by the bell crank lever, an operative connection between the universal bar and the rock shaft, means for returning the rock shaft to its initial position, a plurality of ejector rods each adapted to be engaged and operated by one of the pins on the rock shaft, means for imparting a drop motion to the outer end of each ejector rod after a coin has been ejected and a detachable plate carrying a plurality of coin troughs into which the ends of the ejector rods can enter as set forth.
17. In a coin delivery machine the combination of a plurality of keys, a plurality of longitudinally movable selective strips, an operative connection between each key and the selective strips, a rock shaft, a plurality of pins so mounted on the rock shaft as to be rotatable therewith but longitudinally movable thereon, an operative connection between the selective strips and the pins on the rock shaft, operative connections between

the strip-moving keys and the rock shaft whereby the shaft is rocked when a key is depressed, a plurality of ejector rods each adapted to be engaged and operated by one of the pins on the rock shaft, a rocking plate supporting the outer ends of the ejector rods, means for rocking this plate after the ejection of a coin, means for returning the plate to its initial position and a plurality 10 of coin troughs into which the ends of the ejector rods can enter as set forth.

18. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever 15 operating to shift one or more selective strips, a rock shaft, a plurality of pins so mounted on the rock shaft as to be rotatable therewith but longitudinally movable thereon, an operative connection between the selective 20 strips and the pins on the rock shaft, a universal bar disposed in a position to be engaged by the key mechanism when a key is depressed, an operative connection between the universal bar and the rock shaft, a plurality 25 of ejector rods each adapted to be engaged and operated by one of the pins on the rock shaft, a rocking plate supporting the outer ends of the ejector rods, means for rocking this plate after the ejection of a coin, means for returning the plate to its initial position and a plurality of coin troughs into which the ends of the ejector rods can enter as set forth.

19. In a coin delivery machine the combination of a plurality of keys, a plurality of key rods each movable longitudinally by the depression of a key, a plurality of longitudinally movable selective strips, a plurality of bell crank levers one arm of each of which is 40 engaged by a key rod when a key is depressed this arm being of such length that at a predetermined point in their joint movement the end of the key rod will be disengaged from the lever arm and the key rod free to 45 continue its longitudinal movement while the lever arm is locked by the key rod until such time that the rod returns to its position of rest the other arm of each lever operating to shift one or more selective strips, a 50 rock shaft, a plurality of pins so mounted on the rock shaft as to be rotatable therewith but longitudinally movable thereon, an operative connection between the selective strips and the pins on the rock shaft, a universal 55 bar disposed in a position to be engaged by the key mechanism when a key has been depressed and a key rod moved to the extent necessary to complete the movement of the bell crank lever operated there-

by and position the selective strip or strips 60 controlled by the bell crank lever an operative connection between the universal bar and the rock shaft, a plurality of ejector rods each adapted to be engaged and operated by one of the pins on the rock shaft, a 65 rocking plate supporting the outer ends of the ejector rods, means for rocking this plate after the ejection of a coin, means for returning the plate to its initial position and a plurality of coin troughs into which the 70 ends of the ejector rods can enter as set forth.

20. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, means for returning to their initial positions those selective strips which have been shifted, a rock shaft, a plurality of pins so mounted on the rock shaft as to be rotatable therewith but longitudinally movable thereon, an operative connection between each selective strip and a pin on the rock shaft, a universal bar disposed in a position to be engaged by the key mechanism when a key is depressed, an operative connection between the universal bar and the rock shaft, means for returning the rock shaft to its initial position, a plurality of ejector rods each 80 adapted to be engaged and operated by one 85 of the pins on the rock shaft, a rocking plate supporting the outer ends of the ejector rods, means for rocking this plate after the ejection of a coin, means for returning the plate to its initial position and a detachable 90 plate carrying a plurality of coin troughs into which the ends of the ejector rods can enter as set forth.

21. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a rock shaft, a plurality of collars so mounted on the rock shaft as to be rotatable therewith but longitudinally movable thereon, a pin 110 carried by each collar, projections on the selective strips with which engage the arms of the bell crank levers, projections on each selective strip which engage a pin carrying collar on the rock shaft, means whereby the 115 shaft is rocked when a key is depressed, a plurality of ejector rods each adapted to be engaged and operated by one of the pins on 120

the rock shaft and a plurality of coin troughs into which the ends of the ejector rods can enter as set forth.

22. In a coin delivery machine the combination of a plurality of keys, a plurality of key rods each movable longitudinally by the depression of a key, a plurality of longitudinally movable selective strips, a plurality of bell crank levers one arm of each of which 10 is engaged by a key rod when a key is depressed the other arm of each lever operating to shift one or more selective strips, a rock shaft, a plurality of collars so mounted on the rock shaft as to be rotatable therewith 15 but longitudinally movable thereon, a pin carried by each collar, projections on the selective strips with which engage the arms of the bell crank levers, projections on each selective strip which engage a pin carrying 20 collar on the rock shaft, a universal bar disposed in a position to be engaged by the key mechanism when a key is depressed, an operative connection between the universal bar and the rock shaft, means for returning the 25 rock shaft to its initial position, a plurality of ejector rods each adapted to be engaged and operated by one of the pins on the rock shaft, means for imparting a drop motion to the outer end of each ejector rod after a coin 30 has been ejected and a detachable plate carrying a plurality of coin troughs into which the ends of the ejector rods can enter, as set forth.

23. In a coin delivery machine the combination of a plurality of keys, a plurality of key rods each movable longitudinally by the depression of a key, a plurality of longitudinally movable selective strips, a plurality of bell crank levers one arm of each of which 35 is engaged by a key rod when a key is depressed this arm being of such length that at a predetermined point in their joint movement the end of the key rod will be disengaged from the lever arm and the key rod 40 free to continue its longitudinal movement while the lever arm is locked by the key rod until such time that the rod returns to its position of rest the other arm of each lever operating to shift one or more selective 45 strips, means for returning to their initial positions those selective strips which have been shifted, a rock shaft, a plurality of collars so mounted on the rock shaft as to be rotatable therewith but longitudinally movable 50 thereon, a pin carried by each collar, projections on the selective strips with which engage the arms of the bell crank levers, projections on each selective strip which engage a pin carrying collar on the rock shaft, a universal bar disposed in a position to be engaged by the key mechanism when a key has been depressed and a key rod moved to the extent necessary to 55 complete the movement of the bell crank lever operated thereby and position the selective strip or strips controlled by the bell crank lever an operative connection between the universal bar and the rock shaft, a plurality of ejector rods each adapted to be engaged and operated by one of the pins on the rock shaft, a rocking plate supporting the outer ends of the ejector rods, means for rocking this plate after the ejection of 60 a coin, means for returning the plate to its initial position, means for returning to their initial positions those ejector rods which have been operated and a detachable plate carrying a plurality of coin troughs into 65 which the ends of the ejector rods can enter as set forth.

24. In a coin delivery machine the combination of a plurality of keys a plurality of key rods each movable longitudinally by the depression of a key, a plurality of longitudinally movable selective strips, a plurality of bell crank levers one arm of each of which is engaged by a key rod when a key is depressed this arm being of such 70 length that at a predetermined point in their joint movement the end of the key rod will be disengaged from the lever arm and the key rod free to continue its longitudinal movement while the lever arm is locked by the key rod until such time that the rod returns to its position of rest the other arm of each 75 lever operating to shift one or more selective strips, means for returning to their initial positions those selective strips which have been shifted, a rock shaft, a plurality of collars so mounted on the rock shaft as to be rotatable therewith but longitudinally movable 80 thereon, a pin carried by each collar, projections on the selective strips with which engage the arms of the bell crank levers, projections on each selective strip which engage a pin carrying collar on the rock shaft, a universal bar disposed in a position to be engaged by the key mechanism when a key has been depressed and a key rod moved to the extent necessary to 85 complete the movement of the bell crank lever operated thereby and position the selective strip or strips controlled by the bell crank lever an operative connection between the universal bar and the rock shaft, a plurality of ejector rods each adapted to be engaged and operated by one of the pins on the rock shaft, a rocking plate supporting the outer ends of the ejector rods, means for rocking this plate after the ejection of 90 a coin, means for returning the plate to its initial position, means for returning to their initial positions those ejector rods which have been operated and a detachable plate carrying a plurality of coin troughs into 95 which the ends of the ejector rods can enter as set forth.

trolled by the bell crank lever, an operative connection between the universal bar and the rock shaft, a plurality of ejector rods each adapted to be engaged and operated by one of the pins on the rock shaft, means for returning to their initial positions those ejector rods which have been operated and a detachable plate carrying a plurality of coin troughs into which the ends of the ejector rods can enter as set forth.

24. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, means for returning to their initial positions those selective strips which have been shifted, a rock shaft, a plurality of collars so mounted on the rock shaft as to be rotatable therewith but longitudinally movable thereon, a pin carried by each collar, projections on the selective strips with which engage the arms of the bell crank levers, projections on each selective strip which engage a pin carrying collar on the rock shaft, a universal bar disposed in a position to be engaged by the key mechanism when a key has been depressed and a key rod moved to the extent necessary to complete the movement of the bell crank lever operated thereby and position the selective strip or strips controlled by the bell crank lever an operative connection between the universal bar and the rock shaft, a plurality of ejector rods each adapted to be engaged and operated by one of the pins on the rock shaft, a rocking plate supporting the outer ends of the ejector rods, means for rocking this plate after the ejection of a coin, means for returning the plate to its initial position, means for returning to their initial positions those ejector rods which have been operated and a detachable plate carrying a plurality of coin troughs into which the ends of the ejector rods can enter as set forth.

25. In a coin delivery machine the combination of a plurality of keys a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, means for returning to their initial positions those selective strips which have been shifted, a rock shaft, a plurality of collars so mounted on the rock shaft as to be rotatable therewith but longitudinally movable thereon, a pin carried by each collar, projections on the selective strips with which engage the arms of the bell crank levers, projections on each selective strip which engage a pin carrying collar on the rock shaft, a universal bar disposed in a position to be engaged by the key mechanism when a key has been depressed and a key rod moved to the extent necessary to complete the movement of the bell crank lever operated thereby and position the selective strip or strips controlled by the bell crank lever an operative connection between the universal bar and the rock shaft, a plurality of ejector rods each adapted to be engaged and operated by one of the pins on the rock shaft, a rocking plate supporting the outer ends of the ejector rods, means for rocking this plate after the ejection of a coin, means for returning the plate to its initial position, means for returning to their initial positions those ejector rods which have been operated and a detachable plate carrying a plurality of coin troughs into which the ends of the ejector rods can enter as set forth.

length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, a rock shaft, a plurality of pins so mounted on the rock shaft as to be rotatable therewith but longitudinally movable thereon, an operative connection between each selective strip and a pin on the rock shaft, a universal bar disposed in a position to be engaged by the key mechanism when a key has been depressed and a key rod moved to the extent necessary to complete the movement of the bell crank lever operated thereby and to position the selective strip or strips controlled by the bell crank lever an operative connection between the universal bar and the rock shaft, means for returning the rock shaft to its initial position, means for returning the keys and key rods to their initial positions, means for returning to their initial positions the selective strips and with them the bell crank levers and pins on the rock shaft, a plurality of ejector rods each adapted to be engaged and operated by one of the pins on the rock shaft, a rocking plate supporting the outer ends of the ejector rods, means for rocking this plate after the ejection of a coin, means operated by the rock shaft for returning the rocking plate to its initial position, means for returning to their initial positions those ejector rods which have been operated and a detachable plate carrying a plurality of coin troughs into which the ends of the ejector rods can enter as set forth.

26. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, means for returning to their initial positions those selective strips which have been shifted, a rock shaft, a plurality of collars so mounted on the rock shaft as to be rotatable therewith but longitudinally movable thereon, a pin carried by each collar, projections on the selective strips with which engage the arms of the bell crank levers, projections on each selective strip which engage a pin carrying collar on the rock shaft, a universal bar disposed in a position to be engaged by the key mechanism when a key has been depressed and a key rod moved to

the extent necessary to complete the movement of the bell crank lever operated thereby and position the selective strip or strips controlled by the bell crank lever, an operative connection between the universal bar and the rock shaft, means for returning the rock shaft to its initial position, means for returning the keys and key rods to their initial positions, means for returning to their initial positions the selective strips and with them the bell crank levers and pins on the rock shaft, a plurality of ejector rods each adapted to be engaged and operated by one of the pins on the rock shaft, a rocking plate supporting the outer ends of the ejector rods, means for rocking this plate after the ejection of a coin, means operated by the rock shaft for returning the rocking plate to its initial position, means for returning to their initial positions those ejector rods which have been operated and a detachable plate carrying a plurality of coin troughs into which the ends of the ejector rods can enter as set forth.

27. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a selective strip return lever, means operated by the key mechanism for moving this lever clear of the selective strips as they are positioned, means for operating the lever to effect the return to their initial positions of those selective strips which have been positioned, a rock shaft, a plurality of pins so mounted on the rock shaft as to be rotatable therewith but longitudinally movable thereon, an operative connection between each selective strip and a pin on the rock shaft, a universal bar disposed in a position to be engaged by the key mechanism when a key is depressed, an operative connection between the universal bar and the rock shaft, means for returning the rock shaft to its initial position, a plurality of ejector rods each adapted to be engaged and operated by one of the pins on the rock shaft, means for imparting a drop motion to the outer end of each ejector rod after a coin has been ejected and a detachable plate carrying a plurality of coin troughs into which the ends of the ejector rods can enter, as set forth.

28. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such

length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, a selective strip return lever, means operated by the key mechanism for moving this lever clear of the selective strips as they are positioned, means for operating the lever to effect the return to their initial positions of those selective strips which have been positioned, a rock shaft, a plurality of pins so mounted on the rock shaft as to be rotatable therewith but longitudinally movable thereon, an operative connection between the selective strips and the pins on the rock shaft, a universal bar disposed in a position to be engaged by the key mechanism when a key has been depressed and a key rod moved to the extent necessary to complete the movement of the bell crank lever operated thereby and position the selective strip or strips controlled by the bell crank lever, an operative connection between the universal bar and the rock shaft, a plurality of ejector rods each adapted to be engaged and operated by one of the pins on the rock shaft, means for returning to their initial positions those ejector rods which have been operated and a detachable plate carrying a plurality of coin troughs into which the ends of the ejector rods can enter as set forth.

29. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed the other arm of each lever operating to shift one or more selective strips, a selective strip return lever, means operated by the key mechanism for moving this lever clear of the selective strips as they are positioned, means for operating the lever to effect the return to their initial positions of those selective strips which have been positioned, a rock shaft, a plurality of pins so mounted on the rock shaft as to be rotatable therewith but longitudinally movable thereon, a pin carried by each collar projection on the selective strips with which engage the arms of the bell crank levers, projections on each selective strip which engage a pin carrying collar on the rock shaft, a universal bar disposed in a position to be engaged by the key mechanism when a key has been depressed and a key rod moved to the extent necessary to complete the movement of the bell crank lever operated thereby and position the selective strip or strips controlled by the bell crank lever an operative connection between the universal bar and the rock shaft, means for returning the rock shaft to its initial position, means for returning the keys and key rods to their initial positions, means for returning to their initial positions the selective strips and with them the bell crank levers and the pins on the rock shaft a plurality of ejector rods each adapted to be engaged and operated by one of the pins on the rock shaft, a rocking plate supporting the outer ends of the ejector rods, means for rocking this plate after the ejection of a coin, means operated by the rock shaft for returning the rocking plate to its initial position, means for returning to their initial positions those ejector rods which have been operated and a detachable plate carrying a plurality of coin troughs into which the ends of the ejector rods can enter as set forth.

30. In a coin delivery machine the combination of a plurality of keys, a plurality of key rods each movable longitudinally by the depression of a key, a plurality of longitudinally movable selective strips, a plurality of bell crank levers one arm of each of which is engaged by a key rod when a key is depressed this arm being of such length that at a predetermined point in their joint movement the end of the key rod will be disengaged from the lever arm and the key rod free to continue its longitudinal movement while the lever arm is locked by the key rod until such time that the rod returns to its position of rest the other arm of each lever operating to shift one or more selective strips, a selective strip return lever, means operated by the key mechanism for moving this lever clear of the selective strips as they are positioned, means for operating the lever to effect the return to their initial positions of those selective strips which have been positioned, a rock shaft, a plurality of collars so mounted on the rock shaft as to be rotatable therewith but longitudinally movable thereon, a pin carried by each collar projection on the selective strips with which engage the arms of the bell crank levers, projections on each selective strip which engage a pin carrying collar on the rock shaft, a universal bar disposed in a position to be engaged by the key mechanism when a key has been depressed and a key rod moved to the extent necessary to complete the movement of the bell crank lever operated thereby and position the selective strip or strips controlled by the bell crank lever an operative connection between the universal bar and the rock shaft, means for returning the rock shaft to its initial position, means for returning the keys and key rods to their initial positions, means for returning to their initial positions the selective strips and with them the bell crank levers and the pins on the rock shaft a plurality of ejector rods each adapted to be engaged and operated by one of the pins on the rock shaft, a rocking plate supporting the outer ends of the ejector rods, means for rocking this plate after the ejection of a coin, means operated by the rock shaft for returning the rocking plate to its initial position, means for returning to their initial positions those ejector rods which have been operated and a detachable plate carrying a plurality of coin troughs into which the ends of the ejector rods can enter as set forth.

31. In a coin delivery machine the combination of a plurality of keys, a plurality

of key rods each movable longitudinally by the depression of a key, a plurality of longitudinally movable selective strips, a plurality of bell crank levers one arm of each 5 of which is engaged by a key rod when a key is depressed this arm being of such length that at a predetermined point in their joint movement the end of the key rod will be disengaged from the lever arm 10 and the key rod free to continue its longitudinal movement while the lever arm is locked by the key rod until such time that the rod returns to its position of rest the other arm of each lever operating to shift 15 one or more selective strips, a selective strip return lever, means operated by the key mechanism for moving this lever clear of the selective strips as they are positioned, means for operating the lever to effect the 20 return to their initial positions of those selective strips which have been positioned, a rock shaft, a plurality of collars so mounted on the rock shaft as to be rotatable therewith but longitudinally movable thereon, a 25 pin carried by each collar, projections on the selective strips with which engage the arms of the bell crank levers, projections on each selective strip which engage a pin carrying collar on the rock shaft, a universal bar 30 disposed in a position to be engaged by the key mechanism when a key has been depressed and a key rod moved to the extent necessary to complete the movement of the bell crank lever operated thereby and po-

sition the selective strip or strips controlled 35 by the bell crank lever mechanism comprising toothed quadrants pinions gearing therewith levers and links constituting an operative connection between the universal bar and the rock shaft, means for returning 40 the rock shaft to its initial position, means for returning the keys and key rods to their initial positions, means for returning to their initial positions the selective strips and with them the bell crank levers and 45 pins on the rock shaft, a plurality of ejector rods each adapted to be engaged and operated by one of the pins on the rock shaft, a rocking plate supporting the outer ends of the ejector rods, means for rocking this 50 plate after the ejection of a coin, means operated by the rock shaft for returning the rocking plate to its initial position, means for returning to their initial positions those ejector rods which have been operated, a 55 detachable plate carrying a plurality of coin troughs, an opening in each coin trough in which lies the end of an ejector rod and a hopper into which fall the coins ejected from the coin troughs as set forth.

In testimony whereof I have signed my name to this specification in the presence of two subscribing witnesses.

SAMUEL RANDELL.
